Primary Examiner — Zenia Bennett(74) *Attorney, Agent, or Firm* — Smith Moore Leatherwood LLP; Thomas W. Epting(57) **CLAIM**

The ornamental design for a swim noodle, as shown and described.

DESCRIPTION

FIG. 1 is a perspective view of a swim noodle showing our new design;

FIG. 2 is a perspective view of a front end thereof;

FIG. 3 is a left side view thereof;

FIG. 4 is a right side elevational view thereof;

FIG. 5 is a top plan view thereof;

FIG. 6 is a bottom plan view thereof;

FIG. 7 is a front end view thereof; and,

FIG. 8 is a rear end view thereof.

The dashed broken lines shown in the drawing figures are for illustrative purposes only and form no part of the claimed design.

The dot-dash broken lines represent boundaries that form no part of the claimed design.
